UNITED STATES PATENT OFFICE

2,018,346

WINDOW SASH LOCK

Harper A. Busby, Chicago, Ill.

Application June 18, 1934, Serial No. 731,034

8 Claims. (Cl. 70—14)

The present invention especially relates to improvements on window sash locks.

Among the objects of the present invention is to provide a novel locking device for window sashes which may be easily manufactured, fabricated at small cost, and readily placed in position, a device which is foolproof, troubleproof, rattleproof, weatherproof and burglarproof.

Heretofore, the sashes in a window have been locked by means of a rotatable member secured to one of the sashes which has been provided with a cam surface engageable with a latch or locking member on the other of the sashes. Such locking means is usually placed on the oppositely disposed members of the sash frames and is readily accessible for those desiring to gain entrance therethrough merely by cutting or breaking a small portion of the pane of glass in either one of the sashes adjacent thereto. Such a device is therefore not burglarproof, and is extremely objectionable on this account.

One of the objects of the present invention is to provide a novel locking means adapted to be readily connected to these frame members of sashes or the like, which is burglarproof and cannot be readily manipulated or operated from the exterior of the window sashes even though the panes of glass adjacent thereto may be cut or broken.

Another object of the present invention is to provide a novel locking means for sashes of a window, which is normally operated with a key and which is adapted to draw these frame members together to provide an effective weatherproof joint between the same.

Another object within the purview of the present invention is to provide a novel locking device invisible from the exterior of the sash members of a window and substantially invisible from the interior.

The present invention further comprehends the idea of providing novel locking means in sashes of a window construction, so disposed in these sashes that the same may be locked together to provide for suitable ventilating of the room or compartment, yet preventing access thereto through the window.

A still further object of the present invention is to provide a novel locking device for window sashes which, when operated, is automatically released from its locking engagement with these sashes so that the same may be moved relative to one another.

The invention further includes the idea of providing a novel locking device which is substan-

tially invisible from the interior, one which quickly and easily draws the sashes together to provide a weather-tight joint therebetween and one which permits easier cleaning of the windows inasmuch as the same is substantially entirely closed and is not in the way of the individual performing this operation.

Other objects, features, capabilities and advantages are comprehended by the invention, as will later appear and as are inherently possessed thereby.

Referring to the drawing:

Figure 1 is a fragmentary view in elevation of relatively movable sash members of a window construction disclosing an embodiment of the present locking device operatively associated therewith;

Figure 2 is a fragmentary view in elevation of relatively movable sash members of a window construction disclosing an embodiment of the present invention attached thereto whereby a suitable opening in the window construction is provided for ventilating purposes;

Figure 3 is an enlarged fragmentary view in cross section taken through the locking device as disclosed in Figure 1 of the drawing; and

Figure 4 is a fragmentary view in cross section of window sashes disclosing a locking device of modified construction.

Referring now more in detail to the drawing and more particularly to Figures 1 and 3 thereof, a locking mechanism 2 made in accordance with the present invention is disclosed in association with sashes 4 and 6 of a window construction, these sashes having oppositely disposed frame members 8 and 10, respectively. The frame member 10 of the lower sash member 6 is formed with a horizontally disposed opening 110 adapted to receive the sleeve 112 of the locking device. This sleeve 112 frictionally engages in the opening 110 and is provided with a cap or closure member 114 threadedly engaging the same at its outer end, which cap is flush with the inner face of the frame member and is formed with an opening 116 therethrough. The inner end of the sleeve 112 is formed with an opening 118 through which extends a locking member 120. Locking member 120 is formed with an enlarged head 122 movable within the sleeve 112, a washer 123 being disposed adjacent thereto which forms an abutment for a coil spring 124, which coil spring at its other end abuts a washer or the like 126 disposed adjacent the inner end of sleeve 112.

The inner end of locking member 120 is provided with threads engageable with the internal

threads of a sleeve member 128 disposed in the frame member 8, this sleeve member being secured to the frame member as by means of the screws or the like 130.

5 The head 122 of locking member 120 is formed with a non-circular recess or depression 132 adapted to receive a non-circular shank of a key which may be introduced through the opening 116 of closure member 114. It will be apparent, therefore, that when the key is in engaging relation with the head 122 of locking member 120, the locking member 120 may be either screwed into engagement with the sleeve 128 or released from its threaded engagement therewith. 10 The threads at the inner end of locking member 120 are of sufficient pitch to effect a complete locking engagement between sash members 8 and 10 by one or more rotations of the locking member 120. When the locking member 120 is moved into engagement with the sleeve 128 and rotated, the sash member 8 is drawn into intimate association with frame member 10 to effect a weather-tight joint therebetween, the coil spring serving to maintain this tight joint. This tight 15 engagement prevents rain, dirt, dust or other foreign substances from gaining access into the house, and prevents rattling of the sashes. It will also be apparent that the locking device is not visible from the exterior of the window. When 20 it is desired to move these sashes relative to one another, the key may be introduced through opening 116 into engaging relation with head 122 of locking member 120 and rotated to effect a disengagement of the threads at its inner end with the sleeve 128. The locking member 120 at this 25 time, under the impulse of coil spring 124, will move to the left as shown in Figure 3 so that the inner end of this locking member 120 is moved out of the path of sash member 8. The sashes 30 may then be moved as desired.

In Figure 4 of the drawing, a locking device 134 is shown in association with the frame members 8 and 10, which locking device corresponds somewhat to the locking device shown in Figure 3 of the drawing. In this embodiment, frame member 8 is provided with sleeve 128 secured thereto by means of the screws 130, which construction corresponds to the structure shown in Figure 3 of the drawing. Frame member 10 is likewise provided with sleeve 112 closed by means of closure member 136 formed with an opening 138. The inner end of the sleeve 112 is formed with opening 118 adapted to receive the inner end of locking member 140, the outer end of this locking member being disposed within the opening 138 of the member 136. Locking member 140 is formed at its outer end with a knurled head 142 adapted to be grasped between the thumb and fingers for rotating the same. As in the embodiment shown in Figure 3 of the drawing, the inner end of the locking member 140 is threaded to engage in the sleeve 128. In order to move the locking member 140 out of the path of frame member 8 upon release and to hold the frame members 8 and 10 tightly together, a coil spring 144 is provided, which coil spring corresponds to coil spring 124. This coil spring is disposed between washer 146 abutting the inner end of sleeve 112 and a washer 148 abutting a collar or shoulder 150 provided intermediate the ends of locking member 140. This locking device operates in substantially the same manner as the locking device of Figure 3 of the drawing, with the exception that instead of providing a removable key member, the knurled head 142 serves to rotate the locking member 140. The

locking member 140 draws the frame member 8 into intimate association with frame member 10 to provide a weather-tight joint therebetween and also prevents rattling of the sashes.

It will be noted that in each of the embodiments, the locking member is tapered at its inner end and is received in a sleeve tapered at the end to guide this locking member. This construction facilitates initial operation of the locking member in the event the frame members are not precisely in their proper relative positions.

As disclosed in Figure 2 of the drawing, the present invention comprehends the idea of using either one of the embodiments disclosed in association with the side frame members of sashes 4 and 6 so that these sashes may be moved into the position disclosed for ventilating purposes. The locking device serves to prevent relative movement of these sashes, yet the openings above and below the sashes 4 and 6 provide suitable openings for ventilating purposes. If desired, it will of course be appreciated that the locked sashes may be moved either into the uppermost part of the window or into the lowermost part of the window in order to provide a larger 25 ventilating space either at the top or bottom of this window construction. It is also contemplated that these locking devices will be placed in a suitable position on the side frame members so that the opening between any one sash member 30 and the window frame will not be sufficiently large to permit access therethrough.

While I have herein described and upon the drawing shown illustrative embodiments of the invention, it is to be understood that the invention is not limited thereto but may comprehend other constructions, arrangements of parts, details and features without departing from the spirit of the invention.

I claim:

1. A locking device for windows, comprising an internally threaded sleeve member adapted to be mounted in a frame member of a window sash, a sleeve member having apertured forward and rear ends and adjacent shoulders with an unobstructed interior therebetween and being adapted to be mounted in an oppositely disposed frame member of another window sash, a locking member mounted in said second-named sleeve, said locking member having threads at one end 40 and an enlarged head having a non-circular recess at the other end, and a coil spring in said second-named sleeve having an end abutting said enlarged head and an end abutting said rear shoulder, said non-circular recess being adapted 45 to receive the shank of a key insertable through the aperture at the forward end of said second-named sleeve member whereby the threaded end of said locking member may be rotated into and out of engagement with the threads of said first-named sleeve when said frame members are in oppositely disposed relation, said coil spring serving to retract said locking member when released from said first-named sleeve member to permit relative movement of said sashes, the shoulder 50 at the forward end of said second-named sleeve member serving as a stop for said locking member when retracted under the action of said spring.

2. A locking device for windows, comprising an internally threaded sleeve member adapted to be mounted in a frame member of a window sash, a sleeve member having an apertured end and an adjacent shoulder and being adapted to be mounted in an oppositely disposed frame member 70

of another window sash, a locking member mounted in said second-named sleeve, said locking member having threads at one end and an enlarged head having a non-circular recess at the other end, and a coil spring in said second-named sleeve having an end abutting said enlarged head and an end abutting said shoulder, said sleeve having a closure member provided with an aperture opposite said recess, said second-named sleeve being unobstructed between said shoulder and said closure member, said non-circular recess being adapted to receive the shank of a key passing through the aperture of said closure member whereby the threaded end of said locking member may be rotated into and out of engagement with the threads of said first-named sleeve when said frame members are in oppositely disposed relation, said coil spring serving to retract said locking member when released from said first-named sleeve member to permit relative movement of said sashes, said closure member serving as a stop for said locking member when retracted under the action of said spring.

3. In a locking device for windows, comprising an internally threaded sleeve member adapted to be mounted in a frame member of a window sash, a sleeve member having apertured forward and rear ends and adjacent shoulders with an unobstructed interior therebetween and being adapted to be mounted in an oppositely disposed frame member of another window sash, a locking member mounted in said second-named sleeve, said locking member having threads at one end and an enlarged head having a non-circular recess at the other end, and a coil spring in said second-named sleeve having an end abutting said enlarged head and an end abutting said rear shoulder, said non-circular recess being adapted to receive the shank of a key insertable through the aperture at the forward end of said second named sleeve member whereby the threaded end of said locking member may be rotated into and out of engagement with the threads of said first-named sleeve when said frame members are in oppositely disposed relation, said coil spring serving to retract said locking member when released from said first-named sleeve member to permit relative movement of said sashes, said threaded end of said locking member and the opening of said first-named sleeve member having tapered cooperating parts to facilitate alignment of said sleeves during the initial locking operation, the shoulder at the forward end of said second named sleeve member serving as a stop for said locking member when retracted under the action of said spring.

4. A locking device for windows, comprising an internally threaded sleeve member adapted to be mounted in a frame member of a window sash, a sleeve member having an apertured end and an adjacent shoulder and being adapted to be mounted in an oppositely disposed frame member of another window sash, a locking member mounted in said second-named sleeve, said locking member having threads at one end and an enlarged head having a non-circular recess at the other end, and a coil spring in said second-named sleeve having an end abutting said enlarged head and an end abutting said shoulder, said sleeve having a closure member provided with an aperture opposite said recess, said second-named sleeve being unobstructed between said shoulder and said closure member, said non-circular recess being adapted to receive the shank of a key insertable through the aperture at the forward end of said second named sleeve member whereby the threaded end of said locking member may be rotated into and out of engagement with the threads of said first-named sleeve when said frame members are in oppositely disposed relation, said coil spring serving to retract said locking member when released from said first-named sleeve member to permit relative movement of said sashes, said closure member serving as a stop for said locking member when retracted under the action of said spring.

5. A locking device for windows, comprising a sleeve member adapted to be mounted in a frame member of a window sash, a sleeve member adapted to be mounted in an oppositely disposed frame member of another window sash, said second named sleeve member having an unobstructed interior and being provided with abutments at its forward and rear ends, a locking member mounted in said second named sleeve and adapted to project from the rear end thereof, said locking member at its forward end having an abutment and a recess adapted to receive the shank of a key insertable through an opening in the forward end of said second named sleeve member whereby said locking member is rotated into and out of locking relation with said first named sleeve, said locking member at its rear end and said first named sleeve member having cooperating locking means operable upon rotation of said locking member to lock the same with said first named sleeve, and a spring disposed between the abutment at the forward end of said locking member and the rear abutment of said second named sleeve member, the abutment at the forward end of said second named sleeve serving as a stop for said locking member when retracted under the action of said spring.

6. A locking device for windows, comprising an internally threaded sleeve member adapted to be mounted in a frame member of a window sash, a sleeve member adapted to be mounted in an oppositely disposed frame member of another window sash, said second named sleeve member having apertured forward and rear ends provided with adjacent abutments and having an unobstructed interior therebetween, a locking member mounted in said second named sleeve, said locking member at its forward end having an abutment and a recess adapted to receive the shank of a key insertable through the aperture at the forward end of said second named sleeve member whereby said locking member is rotated, said locking member having a threaded rear end projecting through the aperture at the rear end of said second named sleeve member engageable with the threads of said first named sleeve, and a coil spring disposed between the abutment at the forward end of said locking member and the rear abutment of said second named sleeve member, the abutment at the forward end of said second named sleeve serving as a stop for said locking member when retracted under the action of said spring.

7. A locking device for windows, comprising a sleeve member adapted to be mounted in a frame member of a window sash, a sleeve member adapted to be mounted in an oppositely disposed frame member of another window sash, said second named sleeve member having an unob-

structed interior and being provided with abutments at its forward and rear ends, a locking member mounted in said second named sleeve and adapted to project from the rear end thereof, said locking member at its forward end having an abutment and a recess adapted to receive the shank of a key insertable through an opening in the forward end of said second named sleeve member whereby said locking member is rotated into and out of locking relation with said first named sleeve, said locking member at its rear end and said first named sleeve member having cooperating locking means operable upon rotation of said locking member to lock the same with said first named sleeve, and a spring disposed between the abutment at the forward end of said locking member and the rear abutment of said second named sleeve member, the abutment at the forward end of said second named sleeve serving as a stop for said locking member when retracted under the action of said spring, the rear end of said locking member and the opening of said first named sleeve member having tapered cooperating parts to facilitate alignment of said sleeves during the initial locking operation.

8. A locking device for windows, comprising a

sleeve member adapted to be mounted in a frame member of a window sash, a sleeve member adapted to be mounted in an oppositely disposed frame member of another window sash, said second named sleeve member having an unobstructed interior and being provided with abutments at its forward and rear ends, a locking member mounted in said second named sleeve and adapted to project from the rear end thereof, said locking member having an abutment, means at the forward end of said locking member whereby the same can be rotated into and out of locking relation with said first-named sleeve from the exterior of the abutment at the forward end of said second named sleeve member, said locking member at its rear end and said first named sleeve member having cooperating locking means operable upon rotation of said locking member to lock the same with said first named sleeve, and a spring disposed between the abutment on said locking member and the rear abutment of said second named sleeve member, the abutment at the forward end of said second named sleeve serving as a stop for said locking member when retracted under the action of said spring. 25

HARPER A. BUSBY.
